TYPEWRITING MACHINE

Filed March 10, 1925

UNITED STATES PATENT OFFICE.

ALPHONSE E. IMBUS, OF CINCINNATI, OHIO, ASSIGNOR TO UNDERWOOD ELLIOTT FISHER COMPANY, OF NEW YORK, N. Y., A CORPORATION OF DELAWARE.

TYPEWRITING MACHINE.

Application filed March 10, 1925. Serial No. 14,379.

This invention relates generally to machines of the general class shown in the patent to Wernery & Smith, No. 1,182,055, dated March 16, 1915. In this patent, a web containing a number of layers of work-sheets is drawn over a rear guide-rail and is led over a carbon-holder mounted on the carriage, the plies of work-webs being interleaved with carbon-sheets carried by said holder. The web and the interleaved carbon-sheets are drawn forwardly around the platen and past the printing point as the work-web is being typed and line-spaced. Then the platen is straightened out in line with the web and the carbon-carriage is returned to its rearward position to co-operate with a new portion of the web; then the typed form is cut off against a knife at the delivery side of the platen, and the operation of typing another set of similar forms is again repeated. The invention is also useful in connection with other varieties of manifolding typewriters.

It is sometimes desired to type a different form, and, in such cases, it is the practice to withdraw the web from the machine together with its corresponding carbon-holder, and place both the web and the carbon-holder in its corresponding box. This avoids the delay of reassembling the carbons between the plies of the web, especially when using the type of carbon-carriage disclosed in the patent to Fortin, No. 1,237,819, granted August 21, 1917.

According to the present invention, the machine is then moved to another section of the desk-top corresponding to the position of another bin in which the desired form is stored, so that another carbon-holder may be fastened to the carriage, and the web to be typed inserted around the platen of the machine.

There may be two or three bins side by side under the desk-top, from any one of which the work may be taken. Each bin, moreover, may be double, as shown in the patent to J. A. B. Smith, No. 1,358,038, of November 9, 1920.

One of the features of this invention is that a desk having a flat top of any kind may be used provided that the same is wide enough to allow the machine to be moved therealong to the different positions corresponding to the positions of the boxes in a lower shelf of the desk.

Another feature is that the standard machine may be used with little or no alteration thereof, it being only necessary to remove the rubber feet and to attach the wheels to the frame by means of screws fitting the tapped holes into which the feet are normally screwed.

Still another feature is the ease and convenience with which this device may be handled.

Furthermore, this device adapts itself to be cheaply manufactured and quickly attached to the existing machines without in any way altering the equipment used, as in many cases it may be desired to increase the number of different forms used on the same machine.

In order to facilitate the placing of the typewriting machine in front of the corresponding bin in the desk, there are provided four rubber wheels operatively mounted under the frame of the machine and fastened thereto, instead of the ordinary rubber feet usually found in this type of a machine. The wheels are provided with means whereby the same may be rendered operative or inoperative, that is to say, they may be clamped stationary while the machine is in use, or they may be allowed to rotate freely when the machine is to be moved from one position to another.

Other features and advantages will hereinafter appear.

In the accompanying drawings,

Figure 1 is a rear view in elevation of a desk having a typewriting machine of the fan-fold type placed thereon, and showing a plurality of web-boxes placed upon a lower shelf of said desk.

Figure 2 is a cross-sectional view in elevation on the line 2—2 of Figure 1.

Figure 3 is a cross-sectional view of one of the wheels showing the means for attaching the same to the frame of the machine.

Figure 4 is a perspective view of the two front wheels mounted upon an adapter plate, and shows means whereby the wheels may be rendered ineffective.

A table or desk is provided comprising standards 10 and a top 11, upon which stands an Underwood continuous billing typewriting machine. This machine comprises a main frame 12 and a rearward extension 13, upon which extension travels a carbon-car-

riage 14, forming part of the typewriter-carriage. A web 15, comprising a number of layers of work-sheets, is drawn over a rear guide-rail 16, and is led over a carbon-holder 17 mounted on the carriage 14, the plies of the work-web being interleaved with carbon-sheets carried by said holder. The webs and interleaved carbon-sheets are drawn forwardly around the platen 18 of the machine and past the printing point indicated by the type-bar 19. The carbon-carriage and the web are drawn forwardly as a form is typed on the web, and then the carbon-carriage is returned to its rearward position to co-operate with a new portion of the web, and the typed form is cut off against a knife. The process is then repeated to type another set of similar forms.

According to one feature of this invention, it is sometimes desired to remove one of the forms from the machine and substitute another one thereof. To this end there is provided a shelf 20, beneath the top of the desk and supported by the standards 10, on which there may be placed a plurality of web containers or boxes 21 having a rear opening through which the fan-folded webs may be unfolded and drawn out of the boxes as needed. When not in use, the webs are left idle in the boxes, and the corresponding carbon-holder may also be placed in the box upon the web as shown in Figure 2. The boxes comprise bottom and side walls respectively numbered 22 and 23, and are laid upon the shelf 20. There may be provided any number of boxes as required, six being shown in the drawings grouped in sets of two, one over the other.

In order that the machine may be positioned in front of the box containing the particular form of web to be used, and in order to render the operation simple and convenient, the frame of the machine is provided with wheels 24 operatively mounted beneath the frame 12. Said wheels are mounted on angular plates 25, which are in turn fastened to the frame 12 by means of screws 26, designed to fit the tapped holes into which the feet are screwed, so that the feet may be taken off the machine and the wheels attached thereto.

The wheels 24 are revolvably mounted on studs 27, which are fast to the angular plates 25, by means of nuts 28, screwing into the threaded portion 29 of the studs 27. The plates 25 comprise the two sides or wings of the angular section, a horizontal wing 30 in which the holes 31 are pierced in a position corresponding to the tapped holes in the frame 12, and a vertical wing 32 which carries the studs 27.

The four rubber wheels 24 are provided to facilitate the shifting of the machine from one side to the other of the desk, in a position in front of the box from which it is

desired to withdraw the form. It is obviously necessary to provide means whereby the wheels may be rendered ineffective during the operation of the machine; otherwise the machine would be moved out of place when spacing the carriage. To this end there is provided a lock whereby the two front wheels may be either rendered operative or inoperative by simply swinging a handle 33 either in a clockwise or a counterclockwise direction. The clamping means illustrated in the drawings comprise a threaded portion 34 at the end of the stud 27, a washer 35 to increase the frictional surface on the hub of the wheels 24, and a nut 36 screwing on the threaded portion 34. The handle 33 forms an integral part of the nut 36, and serves as a means for either loosening the wheels or binding them in a fixed position. The two rear wheels are always operative, there being provided no means for binding them in a fixed position, and, instead of the binding nut and handle provided in the two front wheels, there are provided cotter-pins 37 to hold the wheels in place.

Another feature relates to the structure of the wheels themselves which comprise a hard rubber core 38 and an outer soft rubber tire 39, the function of which is to stick to the table when the wheels are locked, thereby preventing the machine from creeping away when being operated. The core of the wheels is made of hard rubber, to provide a resilient hold for the clamp and at the same time to render the wheels stiff enough to withstand the weight of the machine.

To prevent the machine from sliding off the table, there is provided a cross-bar 40 at the ends of the desk-top; thus the travel of the machine is limited within the width of the desk-top. The bars are made the full depth of the desk-top to which they are fast to interpose the wheels 24 and to check their rolling on the table.

Variations may be resorted to within the scope of the invention, and portions of the improvements may be used without others.

Having thus described my invention, I claim:

1. In combination, a typewriter table, a typewriting machine, a magazine for supplying manifold webs to said typewriting machine, the magazine comprising a set of web-containers arranged in tiers, and the typewriter being mounted on wheels for movement laterally along the table to place the typewriter in a position adjacent to any container, and means for locking said wheels against lateral movement.

2. In combination, a typewriter table, a typewriting machine, a magazine for supplying manifold webs to said typewriting machine, the magazine comprising a set of web-containers arranged in tiers, and the

typewriter being mounted on wheels for movement laterally along the table to place the typewriter in a position adjacent to any container, and means for locking said wheels 5 against lateral movement, said means comprising a pivot upon which the wheels are revolutely mounted, and a mechanism whereby the wheels may be clamped on their corresponding pivots, so as to prevent the accidental or voluntary shifting of the machine 10 along the table.

3. In combination, a desk having a flat top, a typewriting machine laterally displaceable thereon, a plurality of web-containers beneath the desk-top disposed side by side along a shelf in the desk, said containers having an opening through which a fan-folded web may be fed to the machine, and means whereby the machine may be brought 15 into cooperating position with any of the containers on the shelf.

4. In combination, a desk having a flat top, a typewriting machine laterally displaceable thereon, a plurality of web-containers beneath the desk-top disposed side by side along a shelf in the desk, said containers having an opening through which a fan-folded web may be fed to the machine, and means whereby the machine may be brought 25 into cooperating position with any of the containers on the shelf, said means including a plurality of wheels, a plate fast to the frame of the typewriting machine, studs fast to said plate and serving as a pivot upon 30 which the wheels are revolutely mounted, and clamps whereby the wheels may be rendered inoperative.

5. In combination, a desk having a flat top, a typewriting machine laterally displaceable thereon, a plurality of web-containers beneath the desk-top disposed side by side along a shelf in the desk, said containers having an opening through which a fan-folded web may be fed to the machine, and means whereby the machine may be brought 40 into cooperating position with any of the containers on the shelf, said means including a plurality of wheels, a plate fast to the frame of the typewriting machine, studs fast to said plate and serving as a pivot upon 45 which the wheels are revolutely mounted, and clamps whereby the wheels may be rendered inoperative, said clamps comprising a threaded portion at the end of the studs supporting the wheels, and a nut having a handle through which the wheels may be clamped, the supporting plate thereby rendering the wheels ineffective, and consequently preventing the movements of the 55 machine along the top of the desk.

6. The combination of a desk having a flat top, a typewriting machine, a plurality of boxes for work-webs to be fed to the machine, movable means supporting said machine upon said desk for translation, to 65

permit said machine to be shifted laterally along the top of said desk, means whereby the machine may be clamped in stationary position in front of any of said boxes, said boxes being arranged side by side beneath 70 the top of the desk, and a shelf upon which said boxes are supported in a fixed position, feeding openings being provided through which the webs are drawn out and fed to the machine.

7. In combination, a desk having a flat top, a typewriting machine of the continuous billing type, laterally movable on and along the top of the desk, a plurality of web-containers disposed side by side along 75 the rear of the desk, said containers having openings through which the fan-folded webs may be fed from the containers to the machine, means for moving the machine laterally on the desk-top into co-operating 80 position with any one of the containers, and means for holding the machine in said co-operating position against lateral movement during the typewriting operation.

8. In combination, a desk having a flat top, 90 a continuous billing typewriting machine on said top, laterally shiftable on and along said top, to register with any one of a plurality of web-containers, a plurality of web-containers disposed side by side along the 95 rear of said top, said containers provided with openings through which the webs may be fed from the containers to the machine when it is registered with any one of said containers, supporting wheels under the 100 machine for shifting it from side to side on the top of the desk, in register with any one of the containers, braking mechanism for locking the wheels against movement of the machine during the typewriting operation 105 when it is in its co-operating register with any one of the containers for feeding the web to the machine, and a soft rubber tread on the wheels to stick to the top of the desk when the wheels are locked with 110 the machine in said co-operating position for preventing the machine from creeping on the table out of said co-operating position when being operated.

9. The combination of a desk having a flat 115 top, a shelf under said top upon which a plurality of web-containers arranged in tiers are laterally disposed, a typewriting machine of the continuous billing type arranged to be shifted laterally along the top 120 of the desk to positions co-operating with any of the containers, and means whereby the typewriting machine may be clamped in a fixed position co-operating with any of the containers.

10. In combination, a desk having a flat top, and a plurality of web-containers arranged in tiers beneath the desk-top, and each container having an opening through 125 which a fanfolded web may be fed to a type- 130

writing machine of the continuous billing type disposed to be shifted along the desk-top into positions co-operating with any of the web-containers.

- 5 11. In combination, a desk having a flat top, a plurality of web-containers arranged in tiers beneath the desk-top, a typewriting machine of the continuous billing type disposed to be shifted laterally along the desk

10 top into positions co-operating with said

containers, including supporting plates fast to the frame of the machine, studs fast to said plates and wheels revolubly mounted on the studs, and means to render some of the wheels inoperative including binding 15 screws and handles therefor, whereby the wheels may be clamped against the supporting plates.
